CENTER EXTENSION TABLE WITH DETACHABLE HINGED SUPPORTS

William M. Costanzo, Weehawken, N. J.

Application April 17, 1948, Serial No. 21,588

5 Claims. (Cl. 311—44)

1

This invention relates to combination articles of furniture, particularly of the kind ordinarily used in a dining room.

According to the invention, there is provided a combination comprising a pair of end-table units, a pair of folding-arm-type extension devices, and a plurality of table leaves, with the latter employable in larger or smaller numbers according to the desired seating capacity of the new article of furniture when the same is used as a single table for seating a desired group of persons, as for dining or any other purpose.

Also according to the invention, certain arm elements of said devices are so inter-connected, and certain of them are so permanently connected to said units, and certain of them are so connected to be readily disconnectable from said units, that, at will, and quickly and conveniently, the combination may be arranged to provide a table of the proper size to seat say 14 persons, or a table of the proper size to seat say six persons, or a table, as a substantially round one, of a proper size to seat say four persons, or two end-tables each usable as an ordinary end-table is used.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a perspective view showing an embodiment of the invention as now favored, arranged to carry five table-top leaves, and with three of such leaves in place as indicated in dot and dash lines.

Fig. 2 is a top plan view of said embodiment, arranged to carry two of the leaves, with these leaves in place as indicated in dot and dash lines.

Fig. 3 is a view similar to Fig. 2, but showing said embodiment arranged to have the table top consist solely of the tops of the two end-table units.

Fig. 4 is an elevational view, partially broken away, looking in the direction of the arrows 4 of Figs. 1 and 5.

Fig. 5 is also an elevational view of the unit last-mentioned, this view being a section taken on the line 5—5 of Fig. 1.

Fig. 6 is an elevational view of the end-table unit at the left in Fig. 1, this view being a section taken on the line 6—6 of Fig. 1.

Fig. 7 is a horizontal section, taken substan-

2

tially on the line 7—7 of Fig. 5, but with here omitted any showing of the three table legs and the facia shown in Figs. 4 and 5.

Fig. 8 is an enlarged vertical section, taken substantially on the line 8—8 of Fig. 7, showing one of the two like spring-pins employed in connection with the two end-table units.

Fig. 9 is a top plan view, as in Fig. 3, but showing, in broken lines, the locations of two fixed pivot pins (these also indicated in broken lines in Figs. 5 and 6) relative to the locations of the two spring-pins, and also showing, in broken lines, the cross-beam and rest-block couples by the aid of which said spring-pins and their associated elements are mounted in place.

Fig. 10 is a somewhat enlarged fragmentary view, showing in top plan meeting end portions of two arms of one of the two folding-arm-type extension devices.

Fig. 11 shows the same parts as in Fig. 10, in bottom plan.

Fig. 12 is a view similar to Fig. 10, but showing meeting end portions of two arms of the other of said extension devices.

Fig. 13 shows the same parts as in Fig. 12, but in bottom plan.

Fig. 14 illustrates, in perspective, and in connection with parts corresponding to those seen in Figs. 12 and 13, a modified construction.

Referring to the drawings more in detail, the embodiment shown includes two end-table units 20 and 21, having variously adjustable relative thereto a pair of folding-arm-type extension devices one of which is marked as a whole 22 in Fig. 1 and the other of which is marked as a whole 23 in Fig. 1.

The extension device 22 comprises an arm 24 permanently pivoted at one end to the unit 20, as by a suitable installed vertical pivot pin 25 (see Fig. 9; and also Figs. 2, 3 and 6); an intermediate arm 26 permanently hinged as at 27 to the other end of the arm 24; and a shorter arm 28 connected to the arm 26 by a hinge 27a having a pintle headed at its top and so readily upwardly removable for convenient hinge breakdown when desired. The shorter arm 28 is instantaneously releasably pivotally connected to the end-table unit 21 by a spring-pin 29 as indicated in Fig. 9, which pin is constructed, mounted and operable as will later be described in connection with Figs. 7 and 8.

The arm 24 is vertically apertured at 30, which aperture registers with an aperture 31 through a metal plate 32 secured as indicated in Fig. 13 to the bottom of said arm. The arm 24 also car-

ries an eye 33, for coaction with a hook 34 pivotally carried by the arm 26 and then to hold the arms 24 and 26 extended as in Fig. 1.

The device 23 comprises an arm 34 permanently pivoted at one end to the unit 21, as by a suitably installed vertical pivot pin 35 (see Fig. 9; also Figs. 2, 3, 4, 6 and 7); an intermediate arm 36 permanently hinged as at 37 to the other end of the arm 34; and a shorter arm 38 connected to the arm 36 by a hinge 39 having a pintle headed at its top and so upwardly readily removable for convenient hinge breakdown when desired. Said arm 38 is instantaneously releasably pivotally connected to the unit 20 by a spring-pin like the spring-pin 29 aforesaid and the location of which is indicated in Fig. 9 where the same is marked 29'.

The arm 34 is vertically apertured at 40, which aperture registers with an aperture 41 through a metal plate 42 secured as indicated in Fig. 11 to the bottom of said arm. Said arm 34 also carries a hook 45, for coaction with an eye 46 carried by the arm 38 and then to hold the arms 34 and 36 extended as in Fig. 1.

The arms 36 and 38, opposite the location of the hinge 39, respectively carry hook and eye elements 43 and 44, for coaction in holding these arms extended as in Fig. 1; and the arms 26 and 28 (of the other device 22) respectively carry, opposite the location of the hinge 27^a, similar hook and eye elements for coaction in holding these arms extended as in Fig. 1, in which view the hook and eye elements last-mentioned are hidden behind said arms 26 and 28.

All six arms of the two devices 22 and 23 are of like cross-section, one which is substantially square.

Referring now to Figs. 1, 4, 5 and 7, the unit 21 is shown as comprising a top 47, a skirt 48, three legs 49, 50 and 51, and a cross-beam 52; such cross-beam having its upper limit spaced below the undersurface of the top 47 a distance about equal to the vertical thickness of the arm 28.

Suitably rigidly secured to the rear side of the cross-beam 52 is a rest-block 53, which, together with the cross-beam, provides a mounting for the spring-pin 29 and its associated parts.

Referring to Figs. 7 and 8, and particularly to the latter view, a recess is provided comprising a larger vertical bore 54 and below the same and concentric therewith a smaller bore 55. These bores, transversely thereof, are provided one-half of each in each block 53 and beam 52. The spring-pin 29, having at its bottom an enlarged head 56, extends upwardly through the bore 55 and thence through the bore 54 and thence upwardly through an apertured metal plate 56^a secured as by screws 57 to the tops of the block and the beam.

The spring-pin 29 is provided with a cross-stud 58 for engaging the plate 56^a to limit upward protrusion thereabove of the upper end of the spring-pin, such protrusion yieldingly maintained by an expansible coil spring 59. The spring-pin 29 carries a spacing collar 60 between its head 56 and the bottom of the block 53; to afford an easy tool or hand hold on said head for pulling down the spring-pin to disconnect the arm 28 for removal when desired. With the arm 28 in place, as shown in Fig. 8, the upper end of the spring-pin is rotatively received in a recess 61 extending up into said arm near one end thereof, after said end of the pin 29 passes through an apertured plate 62 suitably attached, by screws 63, to the underside of said arm.

Referring to Figs. 1 and 6, the end-table unit 20 is shown as of similar construction to that of the unit 21. Thus the parts of the unit 20 to which reference characters with primes are applied, correspond, respectively, to the parts of the unit 21 to which reference characters without primes are applied. As will be understood, and as shown in Fig. 6, the rest-block 53' of the unit 20 is opposite that line of extension of the device 23 which is shown in Fig. 1, just as the rest-block 53 is opposite that line of extension of the device 22 which is shown in Fig. 1.

The arm 38 of the device 23, retained in the combination while the arm 28 of the device 22 is so retained, has secured thereto a plate 62' corresponding to the plate 62 of Figs. 5 and 8, and also a recess corresponding to the recess 61 of Fig. 8, for coaction with the spring-pin 29' in the manner already noted in connection with the coaction between the plate 62 and the recess 61 with the spring-pin 29.

The table top 47 of the unit 21 pivotally carries, at its underside near one end of its straight edge, a hook 64, for coaction with an eye 65 on the underside of the top 47' of the unit 20; and said top 47' pivotally carries, at its underside near one end of its straight edge, a hook 66, for coaction with an eye 67 on the underside of the top 47 of the unit 21; these hooks and eyes for coupling the two units 20 and 21, straight edge of one against straight edge of the other, as shown in Fig. 3.

Five table leaves are provided, all alike, and each like the three thereof and the two thereof shown in dot and dash lines at 68 in Figs. 1 and 2. In the table as herein illustrated, each of these leaves is 12" wide.

In the device 22 the longer arms 24 and 26, and in the device 23 the longer arms 34 and 36, are of such lengths that when the parts are arranged as in Fig. 2 the spacing between the facing and parallel straight edges of the tops of the units 20 and 21, is as there shown equal to the sum of the widths of two leaves 68; while the shorter arms 28 and 38, of the devices 22 and 23, respectively, are of such lengths that, when they are present as in Fig. 1, said spacing between the units 20 and 21 is as there shown equal to the sum of the widths of all five of the leaves 68.

Operation: With the parts arranged as in Fig. 1, for the seating of 14 persons, assume that it is desired to rearrange the parts as in Fig. 2, for the seating of six persons.

As a first step, there are bodily removed the arms 28 and 38.

Thus to remove the arm 28, it is merely necessary to free one end of the same from the arm 26 by lifting out the pintle of the hinge 27^a, and to free the other end of the arm 28 from the spring-pin 29 by pulling down on the head 56 of the latter. And to remove the arm 38, it is merely necessary to free one end of the same from the arm 36 by lifting out the pintle of the hinge 39, and to free the other end of the arm 38 from the spring-pin 29' by a similar pull-down of that pin.

The shorter arms 28 and 38 having been removed, for storage say in the same place where some or all of the leaves 68 are stored when not in use, the only remaining operations are, in regard to the device 22, to disengage from its eye the hook beyond the hinge 27^a, double back the arm 26 on the arm 24 at said hinge, and pivotally mount on the spring-pin 29 the end of the arm 24 carrying the plate 32, and, in regard to the device 23, to disengage from its eye the hook opposite

the hinge 37, double back the arm 36 on the arm 34, and pivotally mount on the spring-pin 29' the end of the arm 34 carrying the plate 42.

The parts then become arranged as in Fig. 2, and when the two leaves 68 are added as there indicated, the table is solidly established, for the proper seating of six persons.

Assuming however, it is desired to transform the arrangement shown in Fig. 1 to that shown in Fig. 3, for the proper seating of four persons, all that is necessary to be done is to remove the arms 28 and 38 as above explained, and then, after disengaging the hooks and eyes opposite the hinges 27 and 37, and doubling back the arms 26 and 36 on the arms 24 and 34 also as above explained, swing the arm-groups 24—26 and 34—36 through 90° about the permanently installed pivot pins 25 and 35, respectively.

Thereby the parts are arranged as indicated in broken lines in Fig. 3.

Then, if a single table is desired as in Fig. 3, it is merely necessary to bring together the two units 20 and 21 as there shown and engage the hooks 64 and 66 with the eyes 65 and 67, respectively, as indicated in Fig. 3.

Also, to employ the two units 20 and 21 as individual end-tables, spaced and placed as desired one without regard to the placement of the other, the parts are used as in Fig. 3, but, of course, with the hooks and eyes last-mentioned disengaged.

To prevent endwise mis-alignment of such leaves **68** as are used, as in Fig. 1 or 2, interfitting projections and recesses may be carried by said leaves, along their long sides, with corresponding provisions along the straight edges of the tops **47** and **47'** of the units **20** and **21**, according to a well-known practice in the art of extension-leaf dining tables.

Referring to Fig. 14, there is here illustrated an arrangement which may be used, in relation to the meeting portions of the arms 26 and 28, in lieu of the hinge 27^a with its removable pintle as aforesaid. Said meeting portions in this view are marked 26' and 28'. The portion 28' is shaped to have a transverse end wall subdivision 70, of relatively small height, and therebelow a downwardly forwardly inclined main end wall subdivision 71, and the portion 26' is shaped to have an end wall subdivision 72 matchable against the end wall subdivision 70 and therebelow a downwardly and rearwardly inclined end wall subdivision 73 matchable against the end wall subdivision 71. For holding this matched relation against lateral displacement, a pair of hooks 74 are pivotally carried by the portion 28', and a pair of coating eyes are carried by the portion 26' one of which eyes is seen at 75. When such construction is employed, a like construction will be employed relative to the meeting end portions of the arms 36 and 38.

While I have illustrated and described the preferred embodiments of my invention, it is to be understood that I do not limit myself to the precise constructions herein disclosed and the right is reserved to all changes and modifications coming within the scope of the invention, as defined in the appended claims.

Having thus described my invention, what I claim as new, and desire to secure by United States Letters Patent is:

1. A table comprising a pair of adjacent end-table units each having a table top with adjacent straight edges, a cross beam for each of said end-table units supported at a position spaced beneath the bottom face of said table top, a pair of

extension devices extended parallel to each other between the said straight edges for supporting a plurality of table leaves between said straight edges in a plane common with said table tops, a plurality of table leaves resting on said extension devices between the adjacent straight edges of said table tops, each of said extension devices having an arm, an intermediate arm and a shorter arm arranged in end alignment, means pivotally connecting one end of each of the first-mentioned arms in position between said table top and said cross beam of one of said end-table units, means pivotally connecting one end of each of said intermediate arms to the other end of the respective first-mentioned arm, means releasably connecting one end of each of said shorter arms to the other end of the respective intermediate arm, each of said shorter arms having its other end engaged between the table top and said cross beam of the other of said end-table units, and means releasably retaining the other ends of said shorter arms in between the table tops and said cross beam of the respective end-table unit.

cross beam of the respective end-table unit.
2. A table comprising a pair of adjacent end-table units each having a table top with adjacent straight edges, a cross beam for each of said end-table units supported at a position spaced beneath the bottom face of said table top, a pair of extension devices extended parallel to each other between the said straight edges for supporting a plurality of table leaves between said straight edges in a plane common with said table tops, a plurality of table leaves resting on said extension devices between the adjacent straight edges of said table tops, each of said extension devices having an arm, an intermediate arm and a shorter arm arranged in end alignment, means pivotally connecting one end of each of the first-mentioned arms in position between said table tops and said cross beam of one of said end-table units, means pivotally connecting one end of each of said intermediate arms to the other end of the respective first-mentioned arm, means releasably connecting one end of each of said shorter arms to the other end of the respective intermediate arm, each of said shorter arms having its other end engaged between the table top and said cross beam of the other of said end-table units, and means releasably retaining the other ends of said shorter arms in between the table tops and said cross beam of the respective end-table unit, said releasable retaining means including a pin slidable on the respective cross beam and spring urged into operative position with each of the other ends of said shorter arms and each of said shorter arms being formed in its other end with a bore engaged by said pin.

3. A table comprising a pair of adjacent end-table units each having a table top with adjacent straight edges, a cross beam for each of said end-table units supported at a position spaced beneath the bottom face of said table top, a pair of extension devices extended parallel to each other between the said straight edges for supporting a plurality of table leaves between said straight edges in a plane common with said table tops, a plurality of table leaves resting on said extension devices between the adjacent straight edges of said table tops, each of said extension devices having an arm, an intermediate arm and a shorter arm arranged in end alignment, means pivotally connecting one end of each of the first-mentioned arms in position between said table top and said cross beam of one of said end-table units, means pivotally connecting one end of each

of said intermediate arms to the other end of the respective first-mentioned arm, means releasably connecting one end of each of said shorter arms to the other end of the respective intermediate arm, each of said shorter arms having its other end engaged between the table top and said cross beam of the other of said end-table units, and means releasably retaining the other ends of said shorter arms in between the table tops and said cross beam of the respective end-table unit, said releasable retaining means including a pin slidable on the respective cross beam and spring urged into operative position with each of the other ends of said shorter arms and each of said shorter arms being formed in its other end with a bore engaged by said pin, said pins having an end accessible below the respective cross beam to be used for withdrawing said pins from the respective bores to free the respective shorter arm.

4. A table comprising a pair of adjacent end-table units each having a table top with adjacent straight edges, a cross beam for each of said end-table units supported at a position spaced beneath the bottom face of said table top, a pair of extension devices extended parallel to each other between the said straight edges for supporting a plurality of table leaves between said straight edges in a plane common with said table tops, a plurality of table leaves resting on said extension devices between the adjacent straight edges of said table tops, each of said extension devices having an arm, an intermediate arm and a shorter arm arranged in end alignment, means pivotally connecting one end of each of the first-mentioned arms in position between said table top and said cross beam of one of said end-table units, means pivotally connecting one end of each of said intermediate arms to the other end of the respective first-mentioned arm, means releasably connecting one end of each of said shorter arms to the other end of the respective intermediate arm, each of said shorter arms having its other end engaged between the table top and said cross beam of the other of said end-table units, and means releasably retaining the other ends of said shorter arms in between the table tops and said cross beam of the respective end-table unit, comprising a pivot pin mounted through the said

one end of the respective first-mentioned arm and mounted on the respective cross beam.

5. A table comprising a pair of adjacent end-table units each having a table top with adjacent straight edges, a cross beam for each of said end-table units supported at a position spaced beneath the bottom face of said table top, a pair of extension devices extended parallel to each other between the said straight edges for supporting a plurality of table leaves between said straight edges in a plane common with said table tops, a plurality of table leaves resting on said extension devices between the adjacent straight edges of said table tops, each of said extension devices having an arm, an intermediate arm and a shorter arm arranged in end alignment, means pivotally connecting one end of each of the first-mentioned arms in position between said table top and said cross beam of one of said end-table units, means pivotally connecting one end of each of said intermediate arms to the other end of the respective first-mentioned arm, means releasably connecting one end of each of said shorter arms to the other end of the respective intermediate arm, each of said shorter arms having its other end engaged between the table top and said cross beam of the other of said end-table units, and means releasably retaining the other ends of said shorter arms in between the table tops and said cross beam of the respective end-table unit, one of said first-mentioned arms having its said one end attached to one of said end-table units at one side thereof and the other of said first-mentioned arms having its said one end attached to the other of said end-table units at the side opposite the side of said one end-table unit to which the said one first-mentioned arm has its said one end attached.
